UNITED STATES PATENT OFFICE

WILLIAM A. MACDONALD, OF LITTLE NECK, NEW YORK, ASSIGNOR TO HAZELTINE CORPORATION, A CORPORATION OF DELAWARE

VACUUM-TUBE SOCKET

Application filed May 21, 1925. Serial No. 31,736.

This invention relates to sockets for vacuum tubes.

It is known that the vacuum tubes because of their delicate structure are microphonic so that when they are mounted in a radio set these tubes are responsive to any shocks or mechanical disturbances of the set in which they are mounted.

In accordance with one feature of the invention, it is proposed to provide resilient springs, preferably of the "leaf" type, contacting with the terminals of the vacuum tube, which springs resiliently support the vacuum tube and thereby absorb mechanical shocks, while serving to make good electrical connections with the terminals.

Another feature of the invention includes the mounting of the resilient contact springs in different planes to support the vacuum tube securely against movement.

Other features of the invention reside in the simplicity of design which results in easy manufacture and assembly with a consequent reduction in cost. Accordingly, it is preferable that the resilient conducting springs be stamped in one piece. This construction not only greatly reduces the cost of manufacture, but also results in improved electrical efficiency by eliminating metal-to-metal contacts which usually corrode and thus introduce undesirable resistance into the circuits.

In the drawings:

Figure 1 represents a side view partially in section of a vacuum tube mounted in the supporting structure, the section being taken on the line 1-1 of Fig. 3;

Figure 2 represents a top view with the bulb of the vacuum tube above the base omitted;

Figure 3 represents a bottom view of the tube supporting arrangement;

Figure 4 is a detailed view of a portion of one of the supporting springs.

Referring to the figures: 5 designates a panel or support having an opening therein slightly larger than the base of the vacuum tube generally designated 6. At four points equally spaced about this opening there are provided posts 7, 8, 9 and 22, best shown in

Figures 1 and 3. It will be noted that the pair of posts 7 and 8 are substantially longer than the pair of supporting posts, such as 9 and 22. At the lower end of these posts are mounted by means of screws resilient leaf springs 10, 11, 12 and 13. These springs have a right-angle twist intermediate their ends and terminate in a clip formed by doubling the end of the spring back upon itself and providing this bent back portion with an opening communicating with a kerf extending to the end of the spring as shown in Figure 4. These springs are identical in structure except that springs 10 and 11 are provided with a lug 14 for engaging the lower surface of the base 6 to limit its downward movement. External circuit connections may, of course, be made by securing connecting leads beneath the screw heads shown at 7, 8, 9 and 22, Fig. 3; but, in accordance with common practice, it is usually desirable to form an integral lug, or tab, at or near the end of each spring when the spring is being stamped out so that the connecting leads may be soldered directly to the springs, whereby good electrical unions are assured. The four terminals of the tube instead of extending through the end or lower surface of the base 6, as is now the practice, terminate in buttons, such as 15, 16, 17 and 18. By locating these buttons in pairs, one pair being in a different horizontal plane from the other pair, the tube has no tendency to tip, or rotate in a vertical plane with the buttons as an axis. Furthermore, this arrangement facilitates the electrically efficient location of lead wires within the tube base. The apertures 23, Fig. 4, are preferably of such size that the contact buttons seat into them when the tube is rotated into its permanent position, as indicated at 15 in Fig. 1, and at 15, 16, 17 and 18 in Fig. 3. Thus the apertures 23, together with the upturned portions 24 of the springs, function as stops to limit the rotary movement of the tube in the socket.

In addition, it will be observed that the arrangement shown provides a much greater contact area between each contact button and its complementary spring than would be

obtained if the buttons rested on flat spring surfaces.

The base of the tube is shown provided with a pin 19 arranged to enter an opening 5 in the support 20 which opening communicates with a slot 21 also serving to limit the downward movement of the vacuum tube. This pin 19 and the groove 21 insure the proper connection of the tube elements to their 10 corresponding springs 10 to 13, inclusive. The vacuum tube, however, is supported solely by these springs. The right-angle twist in each spring introduces at least two advantages. First, it allows the contact surfaces of 15 the springs to be parallel to the sides of the tube base, and thus parallel to the effective contact surfaces of the contact buttons; and second, the springs are thus caused to be flexible both horizontally and vertically, i. e., 20 flexible in two planes mutually at right angles, whereby mechanical shocks from all directions are substantially absorbed by the springs, and consequently are not transmitted to the vacuum tube.

25 It will be understood that this disclosure is merely typical of an arrangement in which a vacuum tube is entirely supported by resilient contact springs, which also serve as electrical conductors for the vacuum tube.

30 I claim:

1. A socket for resiliently mounting a vacuum tube having a plurality of terminals, said socket comprising a support having an opening therein adapted to receive the base of 35 a vacuum tube, and flexible shock-absorbing conducting springs secured to said support and adapted to engage said terminals by means of spring-pressed contacts formed by doubling back upon themselves the bifurcated ends of the springs, said springs being 40 twisted so as to engage said terminals with a friction surface at right angles to the plane of said support and so as to be flexible both vertically and horizontally, said springs being 45 the only supporting means for said vacuum tube, whereby said vacuum tube is rendered substantially immune to mechanical vibration of said socket.

2. A socket for resiliently mounting a vacuum tube having a plurality of terminals, said socket comprising a base portion, and flexible shock-absorbing conducting springs secured to said base portion and adapted to engage said terminals, said springs being 55 mounted at different distances from the plane of said base portion, and being the only supporting means for said vacuum tube.

3. A socket for resiliently mounting a vacuum tube having a plurality of terminals, 60 said socket comprising a support having an opening therein adapted to receive the base of a vacuum tube, and flexible shock-absorbing conducting springs secured to said support and adapted to engage said terminals, 65 said springs being flexible both vertically

and horizontally and being mounted on said support adjacent said opening, said springs being the only supporting means for said vacuum tube, certain of said springs being provided with means to limit rotary movement 70 of said vacuum tube.

4. A socket for resiliently mounting a vacuum tube having a plurality of terminals, said socket comprising a base, and flexible shock-absorbing conducting leaf springs secured to 75 said base and adapted to engage said terminals by means of spring-pressed contacts, each of said springs being twisted substantially at right angles so as to be flexible both vertically and horizontally, and being the only supporting means for said vacuum tube, whereby said tube is rendered substantially immune to mechanical vibration of said socket.

5. A socket for resiliently mounting a vacuum tube having a plurality of terminals, said socket comprising a base, and one-piece flexible shock-absorbing conducting leaf springs secured to said base and adapted to engage said terminals by means of spring-pressed contact portions integral with said conducting springs, each of said springs being twisted substantially at right angles so as to be flexible both vertically and horizontally and being the only supporting means for 85 said vacuum tube, whereby said tube is rendered substantially immune to mechanical vibration of said socket.

6. A socket for resiliently mounting a vacuum tube having a plurality of terminals, 100 said socket comprising a base and flexible shock-absorbing conducting leaf springs secured to said base and adapted to engage said terminals, each of said springs being twisted substantially at right angles so as to be flexible in two planes mutually at right angles, said springs being the only supporting means for said vacuum tube, whereby said tube is rendered substantially immune to mechanical vibration of said socket.

7. A socket for resiliently mounting a vacuum tube having a plurality of terminals, said socket comprising a base and flexible shock-absorbing conducting leaf springs secured to said base and adapted to engage said terminals, certain of said springs being provided with means for limiting rotary movement of said vacuum tube, and each of said springs being twisted substantially at right angles so as to be flexible in two planes mutually at right angles, said springs being the only supporting means for said vacuum tube, whereby said tube is rendered substantially immune to mechanical vibration of said socket.

8. A socket for resiliently mounting a vacuum tube having a plurality of terminals, said socket comprising a base and one-piece flexible shock-absorbing conducting leaf springs secured to said base and adapted to 115 120 125 130

engage said terminals by means of spring-pressed contacts, each of said springs being twisted so as to present surfaces in a plurality of planes, whereby said resilient mounting is operative to absorb mechanical vibrations occurring in planes substantially at right angles, respectively, to said first-mentioned planes, with the result that said tube is rendered substantially immune to said vibrations.

9. A socket for resiliently mounting a vacuum tube having a plurality of terminals, said socket comprising a base and flexible shock-absorbing conducting leaf springs secured to said base and adapted to engage said terminals, each of said springs being twisted so as to present surfaces in a plurality of planes, whereby said resilient mounting is operative to absorb mechanical vibrations occurring in planes substantially at right angles, respectively, to said first-mentioned planes, with the result that said tube is rendered substantially immune to said vibrations.

10. A socket for resiliently mounting a vacuum tube having a longitudinal axis and a plurality of terminals arranged about said axis, said socket comprising a base and flexible shock-absorbing conducting leaf springs secured to said base and adapted to engage said terminals so as to be the only supporting means for said vacuum tube, said springs being located about an axis perpendicular to the plane of said base and coinciding with said first-mentioned axis when said tube is mounted in said socket, each of said springs being curved and twisted at right angles so as to be flexible in two planes mutually at right angles, said springs being secured to said base with a curved surface approximately concentric to said second-mentioned axis, whereby said tube may be moved slightly in said socket in both directions along its longitudinal axis and in all directions in a plane parallel to the plane of said base while its longitudinal axis remains substantially perpendicular to the plane of said base.

11. A socket for resiliently mounting a vacuum tube having a plurality of terminals, said socket comprising a planar portion having an opening therein adapted to receive the base of the vacuum tube, and flexible shock-absorbing conducting springs secured to said planar portion and adapted to engage said terminals, said springs being mounted on said planar portion adjacent said opening, and being the only supporting means for said vacuum tube, each spring being curved approximately concentrically with the tube base whereby said tube may be moved slightly in said socket in the plane of said planar portion while the tube is maintained perpendicular to said plane, all of said springs being flexible vertically and certain thereof being provided with means to limit the movement

of said vacuum tube in a direction perpendicular to said planar portion.

12. In a radio apparatus, the combination of a panel board having an opening there-thru, a plurality of contact members carried by the panel board, the wall of the opening in the panel board having a notch, and a radio tube having its base portion extending thru the opening in the panel board and provided with terminals in engagement with the corresponding contact members, said base portion being provided with a stud seated in the notch in the wall of the opening, the notch and the stud having a predetermined relation to insure the engagement of said terminals with the corresponding contact elements when the stud is seated in the notch, and stops carried by certain of the contact members and engaged by the outer end of the neck of the tube to limit the insertion of the tube thru the opening.

In testimony whereof I affix my signature.
WILLIAM A. MacDONALD.
